Inventor:

Charles C. Morrison,
By his att'y, W. H. Richards.

UNITED STATES PATENT OFFICE.

CHARLES C. MORRISON, OF NEW YORK, N. Y.

GOODS CONTAINER.

Application filed January 18, 1921. Serial No. 438,086.

To all whom it may concern:

Be it known that I, CHARLES C. MORRISON, a citizen of the United States, residing in New York, in the county of New York and 5 State of New York, have invented certain new and useful Improvements in Goods Containers, of which the following is a specification.

This invention relates to containers for 10 goods and the like, and has for one object to provide a container of which a phonograph-record forms a completing part.

Another object is to provide a container 15 of which a phonograph-record forms an exterior ornamental part.

Another object is to provide a container as mentioned above, in which the record is removable for playing on a phonograph, and may be restored to form a part of the container 20 after playing.

Other objects of the invention will appear as the description proceeds; and while herein minute details of the invention are described, the invention is not limited to these, 25 since many and various changes may be made without departing from the scope of the invention as claimed.

In the accompanying drawing showing by 30 way of example two of many possible embodiments of the invention,

Fig. 1 is a perspective view of one form of the container;

Fig. 2 is a central vertical sectional view of the same;

Fig. 3 is a plan of another form of container; and

Fig. 4 is a fragmental section taken on line 4—4 of Fig. 3.

My improved container of Figs. 1 and 2 40 comprises, in combination, a round card-board box 5 having vertical walls 6, and a cover 7 for said box; though it is noted that the invention, as claimed is not limited to containers of the shape shown, or to boxes.

The cover 7 comprises a top wall consisting of an ordinary round double or single faced phonograph record 8 with sound-record grooves 9 therein, suitable for playing on a phonograph, which record may relate to the contents of the container or may comprise any kind of record or sound producing groove. The side-walls 12 for said cover are provided with an inturned upper-edge flange 13 engaging over the edge of the record, and with an in-pressed rib 14 engaging beneath the edge of the record and yield-

ably retaining the record in place, whereby the record may be downwardly removed from the cover side-walls 12 for playing the record on a phonograph. 60

In the form of invention shown in Fig. 3, the top wall is square and consists of a base 15 of a squared portion of card-board, thick paper or other material such, for instance, as a page from the well known Bubble Books. On such page, as a base, is mounted a phonograph record 16 or disk of record material. 65

The cover of Fig. 3 is also provided, as in Fig. 2, with side-walls 12' having an in-turned upper-edge flange 13' engaging over the edge of said base 15 and with an in-pressed rib 14' engaging beneath the edge of the base and yieldably retaining said base in place, whereby the base and record together may be downwardly removed from the side-walls for playing the record 16 on a phonograph. 70

When the container is assembled, as in Fig. 1, it is used as a container for any desired class of goods or articles, and is rendered ornamental by the records being exposed as shown. 80

If it is desired to play the record, the cover 7 is lifted off the box 5. Then the record is forced down and out against the yielding support of the rib 14, after which it may be played in the ordinary way. After playing, the record may be restored to the position of Figs. 1 and 2. After use, the box and cover-side-walls may, if desired, be thrown away and the record alone retained in one's collection. 85

I claim as my invention:

1. A container including an exteriorly exposed phonograph record as a constituent part of one of its enclosing walls and forming ornamentation for the container. 95

2. A container including a removable and replaceable exteriorly exposed phonograph record as a constituent part of one of its enclosing walls. 100

3. A container including a removable and replaceable wall including, as a constituent part, an exteriorly exposed phonograph record to supply ornamentation to the outside of the container. 105

4. In combination, a box; and a cover therefor having a removable and replaceable top wall including, as a constituent part, an exteriorly exposed phonograph record and forming the top wall of the con- 110

tainer; said record co-operating with the outside of the cover as a whole to supply ornamentation for the container.

5. A container, comprising a removable and replaceable wall, including, as a constituent part, a phonograph record; said wall being constructed and adapted to be when removed, placed face to face with other similar devices and to be replaced in

10 the container.

6. A container comprising a readily removable and replaceable wall including, as a constituent part, an exteriorly exposed phonograph record; said wall being constructed and adapted to be removed and played on an ordinary phonograph or to be stored away face to face with other similar devices, and to be replaced in the container.

7. In combination, a box; and a cover 20 therefor having a readily removable and replaceable top wall including, as a constituent part, an exteriorly exposed phonograph record.

8. In combination, a box; and a cover 25 therefor having a readily removable and replaceable top wall comprising an exteriorly exposed phonograph record and forming the sole top wall of the container; said wall being constructed and adapted to be removed 30 from the cover and played on an ordinary phonograph or to be stored away face to face with other similar devices, or to be replaced in the cover.

9. In combination, a box; and a cover 35 therefor having a readily removable and replaceable top wall comprising a phonograph record and forming the sole top wall of the container; said wall and the record grooves and record label thereon being exposed and 40 co-operating with the outside of the cover as a whole to supply and increase ornamentation for the container; said wall being constructed and adapted to be, when removed from the cover, played on an ordinary phonograph or to be stored away face 45 to face with other similar devices, or to be replaced in the cover.

10. A container including a removable reversible and replaceable top wall comprising an ordinary phonograph record 50 suitable for playing on a phonograph and having real record grooves and an ornamental label which may relate to the contents of the container and which cooperate with the exterior of the container to supply 55 increased ornamentation.

11. A container comprising, in combination, a box having vertical upstanding walls; and a cover for said box comprising a reversible top wall comprising a phonograph record; and a permanently continuous smooth side wall for said cover provided with an inturned upper edge flange engaging over the edge of said top wall, and an in-pressed rib yieldably engaging beneath the edge of the record and yieldably retaining said record in place, and permitting the record to be downwardly removed from the continuous side wall, for playing the record on a phonograph.

12. A container comprising, in combination, a card-board box having vertical upstanding walls; and a cover for said box comprising a reversible top wall comprising an ordinary round phonograph record suitable for playing on a phonograph and having real record grooves and an ornamental label which may relate to the contents of the container and which cooperate with the exterior of the container to supply increased 80 ornamentation; and a permanently continuous smooth side wall for said cover provided with an inturned upper edge flange engaging over the edge of said top wall, and an in-pressed rib yieldably engaging beneath the edge of the record and yieldably retaining said record in place, and permitting the record to be downwardly removed from the continuous side wall, for playing the record on a phonograph.

CHARLES C. MORRISON.
